UNITED STATES PATENT OFFICE.

CHARLES L. INGALLS, OF LOWELL, MASSACHUSETTS, ASSIGNOR TO JOSEPH A. CORAM, FRANCIS G. SARGENT, AND NATHAN CROSBY, OF SAME PLACE, ONE-FOURTH TO EACH.

SOAP-PRESS.

SPECIFICATION forming part of Letters Patent No. 225,287, dated March 9, 1880.

Application filed August 28, 1879.

To all whom it may concern:

Be it known that I, CHARLES L. INGALLS, of Lowell, in the county of Middlesex and Commonwealth of Massachusetts, have invented certain new and useful Improvements 5 in Soap-Presses, of which the following is a specification.

My invention consists in the lifting-rod pivoted to the cross-head, and provided with a 10 bend and with a hook beveled on its under side, in combination with a shipping-rod, a spring, and a slide provided with a stud to lift the pressed bar out of the female die.

In the accompanying drawings, Figure 1 is 15 a front elevation of a soap-press embodying my invention; Fig. 2, a side elevation of the same; Fig. 3, an enlarged view of the lifting-rod and shipping-rod, and Fig. 4 a cross-section of the periphery of the eccentric and 20 strap.

A is a stout frame, supporting at the top a shaft, B, to which, by means of the pulley C, a rotary motion is communicated, C' being a loose pulley. A gear, D, on said shaft B takes 25 into another gear, D', of larger diameter, on the shaft B'.

To the shaft B' are secured the balance-wheel E and the eccentric F. The eccentric F is provided with an annular ridge, G, on its periphery, which enters a groove, G', cut on the 30 inside of the strap H, which keeps the strap from getting off from the eccentric. The groove G' also serves to retain the oil used for lubricating said strap and eccentric. The strap is provided with an oil-hole, I, which leads into the groove G', and to which an oil-cup, J, may be applied.

The strap is made in halves secured together by screws K K. Below the eccentric 40 is a connecting-rod, L, rigidly secured to strap H, and having its lower end pivoted at Q to the cross-head Z. The cross-head Z is limited to a vertical motion by the upright guide-rods M M, which pass through the cross-head near 45 its ends, and are held in place by brackets N N, attached to the frame A.

Below the cross-head is a punch or male die, O, secured to said cross-head by a screw, S, which turns in the cross-head, so that by loos-

ening the check-nut T the punch O can be 50 raised or lowered by turning it around to increase or diminish its distance from the top of the slide O' at the bottom of the stroke, according as the bar of soap to be pressed is intended to be thicker or thinner.

A horizontal table, P, is supported by the frame A, and is slotted at R to receive the punch O, which fits it. O' is a vertical slide, the upper end of which enters the slot R, and, with the sides and ends of said slot, forms a 60 box or female die, in which the soap is pressed by the punch O. The slide O' runs through a horizontal rail, A', secured to the frame A.

A stud, U, projects from the back of the slide O'. A lifting-rod, V, provided with a 65 bend, V', and a hook, V'', is pivoted at its upper end to the back of the cross-head Z, and runs in a shipping or hooked rod, W, which prevents the rod V from being drawn too far to the right by the spring X. The 70 hook V'' on the lower end of said rod V is beveled on its under side, so that when the cross-head descends, carrying said rod V and hook V'', the hook will slide past the stud U; but when the rod V is drawn up said hook 75 will catch the stud and lift the slide O', which forces the bar or cake of soap up out of the slot R.

The bend V' on the right of the rod V, running in the shipper W, throws the hook V'' to 80 the left and disengages it from the stud U just as the top of the slide O' reaches the top of the table P, and the slide O' then falls by its own weight, the bar of soap being removed by an attendant and an unstamped bar being 85 put in its place before the punch O descends again.

The top of the slide O' and the bottom of the punch O may be engraved with such words or figures as it is desired to impress on the 90 soap.

In soap-presses heretofore used the soap has been pressed into bars and stamped by a blow.

The advantages of my press are, that it applies a great power very gradually to the soap and squeezes out the surplus moisture of the same, that it will do a great amount of work

in a short time, as the attendant has only to feed the machine and remove the stamped bars, instead of also running the press by muscular exertion, and that the thickness of the bar can be regulated.

I claim as my invention—

The combination of the lifting-rod V, pivoted to the cross-head Z, and provided with a bend,

V', and with a hook, V'', beveled on its under side, the shipping-rod W, the spring X, and the slide O', provided with the stud U, as and for the purpose specified.

CHARLES L. INGALLS.
